LIQUID HOMOGENIZING AND THE LIKE
METHOD AND APPARATUSJohn H. Gardner, Belding, Mich., assignor to
Gardner Dairy Equipment Corporation, Grand
Rapids, Mich., a corporation of Michigan

Application January 25, 1936, Serial No. 60,844

11 Claims. (Cl. 99—265)

This invention relates to methods and apparatus for homogenizing liquids or plastic semiliquids and the like.

As is well known, liquids are homogenized by forcing them under pressure through orifices or the like of small sectional area.

Homogenizers heretofore proposed have various objectionable features among which are the enormous liquid pressures necessary to force the liquid through the homogenizing orifices; the difficulty of manufacture of the apparatus, particularly of the orifice portions; the difficulty of cleansing the same to keep them sanitary particularly when milk, cream and other edible materials are the liquids being homogenized; the complications of machinery and accessory apparatus to operate the homogenizing parts of the apparatus.

It is among the objects of this invention, therefore:

20 To provide a homogenizing apparatus in which the above stated defects and objections are obviated;

To provide generally an improved homogenizing apparatus;

25 To provide, in a homogenizing apparatus, an improved form of small area orifice;

To provide an improved method of forming small area orifices for homogenizing purposes;

To provide a homogenizing apparatus, all the parts of which may be conveniently subjected to cleansing and disinfecting processes;

30 To provide a homogenizing device of simplified construction adapted to be installed in a conduit flow line through which liquid to be homogenized may be pumped.

35 Other objects will be apparent to those skilled in the art to which my invention appertains.

My invention is fully disclosed in the following description taken in connection with the accompanying drawings, in which:

40 Fig. 1 is an elevational view, in part diagrammatic, of an apparatus embodying my invention;

45 Fig. 2 is a longitudinal sectional view to an enlarged scale of a homogenizing part or device illustrated in elevation as a part of Fig. 1;

Fig. 3 is a view illustrating to an enlarged scale a fragment of the device of Fig. 2;

Fig. 4 is a view taken from the plane A—A in the direction of the arrows 4—4 of Fig. 2;

50 Fig. 5 is a view taken from the plane A—A from the direction of the arrows 5—5 of Fig. 2;

Fig. 6 is a fragmentary view to a greatly enlarged scale taken from the plane 6—6 of Fig. 3;

55 Figs. 7 and 8 are views similar to Fig. 6 illustrating modifications;

Fig. 9 is a view illustrating to an enlarged scale, the operative characteristics of a pump illustrated in elevation in Fig. 1.

Referring to the drawings, I have illustrated generally at 1 a liquid circulating pump driven by an electric motor 2, the pump and motor being supported on a common base or pedestal 3. The pump 1 and motor 2 may be of any suitable construction but I prefer to employ a pump of the general character of that shown in Fig. 9. 10 This pump comprises a stator 4 having a cylindrical chamber 5 therein and an impeller 6 driven by the motor shaft 7 by an eccentric pin 8. A stationary vane 9 pivoted in a recess 10 in the stator projects into a recess 11 in the impeller 15 to prevent rotation of the impeller about the pin 8.

Upon rotation of the shaft 7, the impeller 6 will be oscillated in the chamber 5 and if conduits 12 and 13 are connected to the chamber 5 on 20 opposite sides of the vane 9, and are connected in a conduit line of flow, liquid may be drawn in at the conduit 12 and expelled under pressure at the conduit 13.

A pump having the characteristics just described 25 is preferred because, as will be apparent, the flow therethrough, and therefore the pressure created thereby, is constant and not undulating. Although the homogenizing parts of my invention to be described will operate with an undulating 30 pressure, I have found that the operation thereof is improved and the homogenizing of liquids thereby is more uniform if the pressure is not fluctuating or undulating. Furthermore, although I have illustrated the type of pump which 35 I prefer to employ, the pump itself forms no essential part of the present invention and it is believed that the brief description thereof hereinbefore and the fragmentary illustration thereof in the drawings will be sufficient. 40

The intake side of the pump at 12 is connected to a source 14 of liquid to be homogenized. If the liquid is cream, milk, or the like, the source 14 may be a pasteurizing apparatus. On the way from the source 14 to the pump, the liquid flows through a strainer 15. The output side of the pump at 13 is connected by a coupling 16 to one side of the homogenizing device proper, to be described, 17, the other side of which, by means 45 of a coupling 18, is connected to a conduit line 19 discharging into any suitable homogenized liquid receptacle which, in the case of homogenizing milk or cream or the like, may be a cooling apparatus 20 from which if desired a conduit 21 may 50

55

conduct the cooled homogenized liquid to suitable receptacles therefor.

The homogenizing device 17 is illustrated in Figs. 2 to 6 inclusive, and in its unitary form in which it is preferred that it be manufactured, comprises two pieces only 22 and 23. As illustrated in Figs. 2, 4, and 5, the device is substantially of full size. The piece 22 comprises peripherally thereof an interiorly threaded flange 24 and the part 23 is exteriorly threaded as at 25 by which the two parts or pieces 22 and 23 may be threaded together. Each piece 22 and 23 has extending axially thereof similar tubular extensions 26 and 27 upon the outer ends of which as at 28—28, preferably like externally threaded coupling portions are provided which may be of well known form by which, in connection with couplings 16 and 18 shown in Fig. 1, a liquid pressure type conduit connection may be made therewith for conduit communication with interior chambers 29 and 30 of the parts 22 and 23.

Confronting faces 31 and 32 of the parts 22 and 23, respectively, are formed as follows. The part 22 has centrally thereof a circular opening 33 forming the inner termination of the chamber 29. Annular shallow grooves 34 and 35 are formed in the faces 31 and 32 providing a flat annular chamber 36 radially spaced from the opening 33 and shallow grooves 37 and 38 similarly provide an annular chamber 38 radially outwardly of the chamber 36. The faces 31 and 32 which are in coinciding planes thus engage each other only on planar annular faces 40, 41, 42 on the part 22, and 43, 44, 45 respectively on the part 23. These faces are preferably ground coplanar so that when the threaded portions 24 and 25 are drawn up together, the pressure of the engagement thereof will all come on the faces 40 to 45, thus sealing these faces mutually with liquid-pressure-proof engagement.

The chamber 38 of the part 23 is closed inwardly thereof by a wall 46 on the outer surface of which the said annular grooves and annular faces of the part 23 are formed and in the center 45 thereof is provided an elevated cone or conoidal projection 47 projecting into the chamber 29.

A plurality of relatively large perforations 48—48 in the wall 46 communicate with the annular chamber 38 and with the chamber 30.

As illustrated in Figs. 3 and 6 and as indicated by the dotted lines 49, a plurality of preferably radial grooves 49 are cut in the planar surface 43 effecting communication between the annular chamber 36 and the chamber 29. A plurality of 55 similar grooves 50 are cut in the annular surface 44, effecting communication between the chamber 38 and the chamber 36. The grooves 49 and 50 are preferably formed by a milling operation and as shown in Fig. 6 are preferably rectangular in cross-section, although the curvilinear form of Fig. 7 or the triangular form of Fig. 8 may be used; and although the grooves are preferably formed in the surfaces 43 of the piece 23, they may be formed as shown in Fig. 8 in the corresponding surfaces 46 of the piece 22.

In operation of the device 17, liquid from the source 14, Fig. 1, is forced by the pump 1 into the chamber 29, Fig. 2, the stream thereof being divided by the projection 47, and the liquid is then forced outwardly radially through the passageways 48—48 into the chamber 36. The passageways 48—48 being of very small cross-sectional area as will be more fully referred to hereinafter, the liquid will, after flowing therethrough, suddenly expand or explode due to the release of

pressure thereon into the chamber 36, the combined action of the pressure induced flow through the passageways 48 and the explosion thereof into the chamber 36 effecting homogenizing of the liquid. The liquid then continues to flow out of the chamber 36 through the passageways 50 and into the chamber 38, and again the homogenizing action is performed thereon. The liquid, now homogenized, flows through the passageway 48 into the chamber 38 and thence through the rest of the system as hereinbefore referred to.

I have found that when the passageways 48—48 formed by the said grooves have a cross-sectional area between .008 square inch to .017 square inch, and of approximately $\frac{1}{2}$ " long, a suitable homogenizing effect will be performed whether the grooves are of the rectangular form of Fig. 6 or of the other forms of Figs. 7 or 8. And, as will be obvious, other forms of grooves may be employed, my invention not being limited to any particular cross-sectional area, form, or length of such groove.

It will furthermore be seen that without complications of structure, the homogenizing effect is of a two-stage type and it will be clearly apparent that other annular groups of small passages corresponding to the passages 48 and 50 may be provided to add other stages of homogenization or that the effect can be produced with a single stage, for example by omitting the stage performed by the grooves 50.

Whereas, furthermore, the grooves 48 have been made radial because of the convenience thereof in milling the same, it thereby being made possible to mill directly across the device and by a single operation mill two aligned diametrically opposite grooves, it will be apparent that the grooves 48 and 50 may be disposed in directions other than radial.

From the foregoing description it will, of course, be apparent that liquid cannot leak along the faces 40 and 43 or 41 and 44 or 42 and 45, because these faces are all coincidental in a single plane, being ground planar for that purpose and being held in pressure engagement by the screw-threaded connection of the two parts 22 and 23, the screwing movement of the two parts being threaded together bottoming on these surfaces.

As illustrated in Fig. 3, the wall 51 of the chamber 38 adjacent the approach end of the groove 48, is disposed outwardly radially from the inner end of said groove. By this means, as the liquid approaches the open end of the groove 48, which as hereinbefore described, is on an elevated face 43, the liquid is given a slight swirling movement indicated by the arrow 52. While this swirling movement is not enough to interfere with the free flowing of liquid into and through the passageway grooves 48, it is sufficient, in case there are small particles of foreign matter in the liquid, to carry said particles across and beyond the opening of the grooves 48 and to prevent their flowing therewith and lodging therein. Any particles which tend to lodge at the entrance of the groove 48 are continuously washed away therefrom by the swirling liquid.

Apparatus of this class, as is well known, must be frequently cleaned. With the construction above described, to clean the device 17 it is only necessary to uncouple it at the couplings 16 and 18 and then to unscrew the two parts 22 and 23 from each other whereupon the small area passageways above described are converted into flat annular surfaces 40 and 41 as illustrated in Fig. 7.

5 and other flat annular surfaces 43 and 44 with radial or other grooves 49 and 50 therein as illustrated in Fig. 4. All of these surfaces being fully exposed to the action of cleansing liquids 5 and utensils such as ordinary brushes may be thoroughly cleaned and disinfected, and by the simplest processes. All of the other surface portions inside and out of the device, as clearly illustrated, can, furthermore, be readily cleaned 10 and the passageways 48 may be of such large diameter as to admit easily passing therethrough a cleansing brush or the like.

I have found that with a homogenizing device as above described, it is not necessary to employ 15 the high pressures such as 5,000 pounds per square inch of liquid heretofore necessary to produce a perfect homogenizing action; low pressure such as 150 pounds per square inch will be found sufficient in most cases. And I believe this 20 to be due to the fact that the passageways through which the liquid is forced may be made of as small cross-sectional area and as great length as desired and may, after being forced or squeezed through the passageways, be exploded or expanded thereafter, stage after stage, 25 as may be desired.

In order to facilitate the grinding of the annular surfaces 43 and 44 of the part 23, and to facilitate the diametrical cutting of the grooves 30 49 and 50, the central projection 47 may be on a separate piece driven into a suitable recess in the partition 46 of the piece 43 as illustrated in Fig. 3.

As stated hereinbefore, my invention is susceptible of various modifications and is not limited to the exact construction illustrated and described, the invention comprehending all changes and modifications which may be made within the spirit of my invention without sacrificing its advantages and within the scope of the appended 40 claims.

In the foregoing, the method and apparatus has been described as directed particularly to the homogenizing of liquids. The apparatus, however, may be used without change for performing other processes on liquids, such for example as emulsifying, viscolizing, etc. It has been found that while homogenizing may be performed at high pressures such as are necessary in prior 50 apparatus, emulsifying is in some cases better performed at low pressures. For example, butter and skim milk can be emulsified back into milk or cream, but if the process is performed at high pressures the butter fat globules will be 55 broken up and the resulting cream will not be suitable for whipping. Again, ice cream mix can be made using whole butter and skim milk or water instead of cream with the usual sugar, gelatin, egg concentrate, etc., and if the whole mixture is run through the device above described, and at the low pressures at which it will operate, 60 the butter and milk or water will be emulsified to a cream consistency at the same time that the mix as a whole is homogenized into a homogeneous smooth mix which when frozen provides ice cream of a much improved consistency and texture.

In some cases, it may be desirable to run the material, to be processed, through the device a 70 number of times successively.

In the following claims the word "homogenizing" is to be taken in this broader sense as inclusive of such other processes and treatments of liquids, semi-liquids, and the like.

75 I claim:

1. In a homogenizing device, a pair of walled housing elements adapted to be connected in a liquid conduit flow line, one housing element having a passageway therethrough and laterally of the mouth of the passageway having a pair of 5 annular concentric elevated planar faces thereon providing an annular recess therebetween, the other housing element having a transverse wall provided with a corresponding pair of annular concentric elevated planar faces thereon providing an annular recess therebetween, means to clamp the two housing elements together with the elevated faces in pressure-sealed engagement, the recesses providing a sealed annular chamber, a plurality of generally radial grooves 10 in one of the annular faces providing communication between the said housing elements, and conduit means extending through the said transverse wall effecting communication between the said annular chamber and the housing having 15 the transverse wall.

2. In a homogenizing device, a pair of walled housing elements adapted to be connected in a liquid conduit flow line, one housing element having a passageway therethrough and laterally 20 of the mouth of the passageway having three annular concentric elevated planar faces thereof providing therebetween two annular recesses, the other housing element having a transverse wall provided with three corresponding concentric 25 elevated planar faces thereof providing therebetween two other annular recesses, means to clamp the two housing elements together with the elevated faces in pressure-sealed engagement, the recesses providing sealed annular chambers, 30 a plurality of generally radial grooves extending across one of the annular faces of each pair of engaged annular faces providing communication between the said passageway of the first-named housing element and one of the annular chambers, 35 and between said annular chamber and the other annular chamber, and a passageway communicating from the outer annular chamber extending through the said transverse wall effecting communication between said annular chamber 40 and the housing having the transverse wall.

3. The homogenizing device described in claim 10 and in which all of the said surfaces are co-planar.

4. In a homogenizing apparatus, a pair of 50 joined fluid conduit elements having jointly a passageway therethrough comprising a fluid inlet in one element and a fluid outlet in the other, the housing elements supporting respectively mutually contacting surfaces, an outer portion 55 of said contacting surfaces circumscribing and outwardly sealing the passageway at the junction of the elements, the passageway comprising branch passages of small cross sectional area disposed between the inlet and outlet and inwardly 60 of the said circumscribing seal, the branch passages comprising grooves formed in a said contacting surface portion of one element and covered by a corresponding said contacting surface portion of the other element, and means to clamp 65 the two housing elements together and to effect pressure on said contacting surfaces.

5. The apparatus described in claim 4 and in which the housing elements are clamped to each other by mutually meshed threads and the said 70 seal is on annular contacting surface portions co-axial of the threads and the grooved surface portions and grooved covering surface portions are annular co-axial of the threads.

6. The apparatus described in claim 4 and in 75

which the housing elements are clamped to each other by mutually meshed threads and the said seal is on annular contacting planar surface portions co-axial of the threads and the grooved surface portions and the grooved covering surface portions are planar and annular co-axially with the threads.

7. The apparatus described in claim 4 and in which the housing elements are clamped to each other by mutually intermeshed threads and the said seal is on planar annular contacting surface portions co-axial of the threads and the grooved surface portions and grooved covering surface portions are annular and co-axial with the threads and co-planar with the said sealing surface portions.

8. A homogenizing device comprising a conduit form housing adapted to be connected in a liquid flow conduit line and to have liquid forced there through under pressure, the conduit housing comprising two parts detachably clamped one upon the other upon mutually engaged surfaces having passages provided therebetween formed by a plurality of grooves in one of said surfaces disposed in the line of liquid flow and covered by opposite portions of the other surface, and portions of the engaged surfaces outwardly of the passages sealing the juncture of the housing parts, and means communicating with said passages adapted to transmit liquid therefrom to an outlet conduit line.

9. In a homogenizing device, a housing comprising two chambers and an intermediate wall and having means for connecting the housing in a conduit liquid flow line for introducing liquid

under pressure to the housing on one side of the wall and conducting the liquid from the other side of the wall, the housing being formed from two elements each having finished surface portions thereon, means to clamp the elements together with one surface upon the other in coinciding pressure sealed engagement therewith, and a plurality of passages extending through the wall comprising grooves in one finished surface portion covered by overlying portions of the other finished surface portion.

10. In a homogenizing device, joined means providing an outer and an inner pair of annular coincident surfaces detachably and sealedly clamped together one upon the other in said pairs, a passageway through the inner surface comprising a radial groove in one inner surface covered by an opposite portion of the other inner surface, means to confinely conduct liquid under pressure through the inner surfaces to the groove and to confinely conduct it away therefrom, and the outer pair of surfaces sealing the juncture of the joined means, and conduit means adapted to conduct liquid transmitted through the groove to a fluid outlet conduit.

11. In a homogenizing device, a pair of detachably joined elements having a wall therebetween, each of said elements having a co-planar portion sealedly engaged and formed to provide a continuous passageway therebetween, means for conducting fluid from a fluid supply conduit to said passageway through a plurality of relatively small orifices, and means conducting fluid from the passageway to a fluid outlet conduit.

JOHN H. GARDNER. 35
